BUILDING STRUCTURE

Frank E. McCabe, Shaker Heights, Ohio, assignor to The Grabler Manufacturing Company, Cleveland, Ohio, a corporation of Ohio

Application June 1, 1935, Serial No. 24,522

4 Claims. (Cl. 189—85)

This invention relates to building structures, and more particularly to face-work building structures, and has for an object the provision of new and improved structures of this character.

In the drawing accompanying this specification and forming a part of this application, I have shown, for purposes of illustration, embodiments which my invention may assume, and in the drawing:

Figure 1 is a fragmentary perspective view of a building structure, embodying the invention, disclosing parts of the same in horizontal section, and disclosing parts broken away to more clearly illustrate the construction,

Figure 2 is an enlarged fragmentary horizontal sectional view, corresponding substantially to the line 2—2 of Figure 1,

Figure 3 is a view similar to Figure 2, corresponding substantially to the line 3—3 of Figure 1,

Figure 4 is an enlarged fragmentary horizontal sectional view, corresponding substantially to the line 4—4 of Figure 1,

Figure 5 is a fragmentary perspective view, similar to Figure 1, and disclosing a different embodiment of the invention, while

Figure 6 is an enlarged horizontal sectional view, corresponding substantially to the line 6—6 of Figure 5.

As shown in Figures 1 through 4 of the drawing, the invention comprises a building structure, wherein a plurality of facing panels 10 are disposed edge to edge and flatwise along the surface of a supporting wall 11, which may be the front wall of a building or the like, and the panels 10 are secured in position along said wall by a plurality of sets of securing means, each set being indicated generally by the reference character 12, and adapted to be positioned between juxtaposed edges of each pair of panels 10; the sets 12 are duplicates in construction and operation and only one of the same will be described in detail.

Each of the sets 12 comprises an elongated member 13, preferably of sheet metal, and channel-shaped in cross-section, having an intermediate portion 14, and integrally formed outwardly extending webs 15, which merge with in-turned overhanging flanges 16, spaced apart to define a continuous slot 17. The intermediate portion 14 of the member 13 is adapted to rest flat against the face of the supporting wall 11, and at intervals along its length is provided with slots 18, each elongated in the direction of the length of the member 13. Associated with each of the slots 18 is an anchoring member 19, com-

prising a screw-bolt 20, extending through the slot 18, having a head 21 bearing against the outer face of the intermediate portion 14, and a shank threaded into a wedge part 22, and the wedge part 22 is encased in an expandable sleeve 23, which may be of lead. The wedge part 22 and sleeve 23 may be accommodated in a suitable cavity 24 formed in the supporting wall 11, and rotation of the bolt 20 serves to draw the wedge part 22 inwardly, and to expand the sleeve 23 into anchoring engagement with the wall of the cavity 24. When all of the anchoring members 19 have been tightened, the member 13 is fixedly secured to the supporting wall 11, and the slots 18 permit necessary movement incident to expansion and contraction under varying conditions.

Cooperating with each of the fixed members 13 is a plurality of connecting members 25, each preferably in the form of an oblong piece of metal sufficiently long to prevent turning when inserted within the channel-shaped formation of the member 13, said connecting members 25 being adapted to be inserted into the channel-shaped formation of the members 13 through transverse slots 26 formed in the flanges 16, then shifted out of line with the slots 26, thereby to present engaging portions 27 adapted to abut the inner surfaces of the overhanging flanges 16. Threaded through each of the connecting members 25, is an actuating screw 28, which extends outwardly through the slot 17, and at its outer end is provided with a kerfed head 29, and carried by the shank of the actuating screw 28 is a clamping member 30, of greater size than the slot 17, and which provided bearing portions 31 and 32 adapted to cooperate with the outer surfaces 33 of the flanges 16 to provide clamping means.

Each of the sets of securing means 12 is adapted to secure juxtaposed edges of a pair of the panels 10 to the supporting wall 11, and the panels 10 are formed for cooperation with the securing means 12, each of the panels 10 comprising a rectangular, channel-shaped formation having an intermediate portion 34, an angularly extending web 35 along one edge of the portion 34, and an angularly extending web 36 along the opposite edge of the portion 34, and the web 35 has an out-turned marginal flange 37 adapted to be clamped between the clamping surfaces provided by the bearing portion 31 of the clamping member 30 and the surface 33 of the adjacent flange 16, while the web 36 has an out-turned marginal flange 38 adapted to be clamped between the bearing portion 32 and the outer surface 33 of the adjacent flange 16.

Installation of the face-work structure is preferably effected by first securing a plurality of the members 13 vertically and in spaced relation along the supporting wall 11, through the medium 5 of the anchoring members 19, the members 13 being spaced apart a distance corresponding to the width of the panels it is desired to use. The clamping means, each comprising the connecting member 25, actuating screw 28, and clamping member 30, are each assembled with respect to the members 13, this being effected by inserting the connecting member 25 through the slots 26. The marginal flanges 37 and 38 of adjacent panels are then inserted between the clamping members 15 30 and adjacent faces 33 of the flanges 16, and the actuating screws 28 tightened. After all of the clamping members 30 have been adjusted, the space between the webs 35 and 36 of the secured panels 10 may be filled with a suitable filling material, indicated at 39, the heads of the actuating screws 28 and anchoring members 19 providing key means for the filling material, and in turn being held thereby against accidental loosening. Although the securing members 13 are shown and 25 described as secured vertically along the supporting wall 11, it will be understood that these members may be disposed horizontally, and the panels 10 secured thereto, or, if desired, the securing members 13 may be arranged both vertically 30 and horizontally to present rectangular formations to which all four edges of the panels 10 may be secured, the panels 10, in this latter case, of course, having all four edges formed as heretofore described to cooperate with the securing 35 means.

Referring to Figures 5 and 6, a somewhat different embodiment of the invention is disclosed, comprising elongated securing members 40 similar to the members 13, each having a channel-shaped body, with an intermediate portion 41, and spaced overhanging flanges 42, the intermediate portion 41 being secured at intervals to the supporting wall 43 by anchoring members (not shown) identical to the anchoring members 45 19 heretofore described. A plurality of clamping means are provided for cooperation with the members 40, each of these clamping means comprising a connecting member 44, actuating screw 45, and a clamping member 46, these parts being 50 identical in construction and operation to the parts 25, 28 and 30 heretofore described, except that the clamping member 46 is somewhat longer than the member 30, and the actuating screw 45 is also somewhat longer than the actuating screw 28. Panels 47 of a type somewhat different from the panels 10 are employed in this embodiment, each having an intermediate portion 48, angular webs 49 and 50, and each of the webs 49 and 50 having an inwardly turned flange 51 55 adapted to rest upon the outer surfaces of the flanges 42. The web portions 49 and 50 of adjacent panels 47 are slotted at intervals, as indicated at 52 for the reception of the ends of the clamping members 46, the slots 52 being sufficiently large to permit the clamping member 46 60 to be rotated about the axis of the actuating screw 45 and enter the slots, after which the actuating screws are screwed home, clamping the panels 47 in position.

After the panels 47 are in position, suitable filling material, indicated at 53, is employed to fill the cracks between the adjoining edges of the panels 47, and the heads of the actuating screws 45 serve as key means for said filling material, 75

and the filling material prevents accidental rotation of the actuating screws.

It will be apparent to those skilled in the art that I have accomplished at least the principal objects of my invention, and it also will be apparent to those skilled in the art that the embodiments herein described may be variously changed and modified, without departing from the spirit of the invention, and that the invention is capable of uses and has advantages not herein specifically described; hence it will be appreciated that the herein disclosed embodiments are illustrative only, and that my invention is not limited thereto. 10

I claim:

1. A building structure of the character described, comprising: a support; a facing member; securing means, channel-shaped in cross-section, and having an intermediate portion, marginal angular webs, and overhanging flanges 20 on said webs, said flanges having slotted openings therein, and said securing means having its intermediate portion secured to said support; and holding means mobile with reference to said securing means and with reference to said facing member, having a portion insertable through said slotted openings and engageable beneath the overhanging flanges of said securing means, and having means extending outwardly of said securing means and engageable with said facing 30 member to hold the same in position with respect to said support. 15

2. A building structure of the character described, comprising: a support; a plurality of juxtaposed facing members, channel-shaped in cross-section, and having angularly extending portions slotted for the reception of fastening means; securing means, channel-shaped in cross-section, and having an intermediate portion, marginal angular webs, and overhanging flanges 40 on said webs, against which said facing members are adapted to bear, said securing means having its intermediate portion fixed to said support; and holding means having a holding portion operatively engaging beneath the overhanging flanges of said securing means, and having an actuating screw extending outwardly between said overhanging flanges and outwardly of said securing means and carrying a clamping member engageable within the slots of said angular portions of said facing members to hold the same in position with respect to said support. 45

3. A building structure of the character described, comprising: a support; a facing member; securing means, channel-shaped in cross-section, and having an intermediate portion, marginal angular webs, and overhanging flanges 55 on said webs, said securing means having its intermediate portion fixed to said support, and the overhanging flanges of said securing means having slotted openings therein; and holding means having a holding portion operatively insertable through said slotted openings and engaging beneath the overhanging flanges of said securing means, said holding means having an actuating 60 screw extending outwardly of said securing means and carrying a clamping member engageable with said facing member to hold the same in position with respect to said support. 65

4. Securing means of the character described, 70 comprising: a securing member, channel-shaped in cross-section, having an intermediate portion, marginal webs, and spaced overhanging flanges on said webs, said flanges being slotted to facilitate insertion of holding means therebeneath; 75

and holding means separable with reference to said securing member, having a portion insertable through the slotted portions of said flanges, and shiftable to engage beneath said flanges, and
5 having means extending outwardly between said overhanging flanges, and outwardly of said

flanges carrying a clamping member, said holding means being so constructed and arranged as to be operable to cause approach of said clamping member toward said overhanging flanges.

FRANK E. McCABE.
